UNITED STATES PATENT OFFICE.

THOMAS H. WILLIAMS AND SAMUEL D. TOMPKINS, OF JERSEY CITY, NEW JERSEY, AND JOHN N. MATLOCK, OF BROOKLYN, NEW YORK.

RADIATOR.

SPECIFICATION forming part of Letters Patent No. 309,811, dated December 23, 1884.

Application filed June 27, 1883. (No model.)

To all whom it may concern:

Be it known that we, THOMAS H. WILLIAMS and SAMUEL D. TOMPKINS, both of Jersey City, in the county of Hudson and State of New Jersey, and JOHN N. MATLOCK, of Brooklyn, Kings county, State of New York, have made an invention of certain new and useful Improvements in Radiators for Steam-Heating; and we do hereby declare that the following, in connection with the accompanying drawings, is a full, clear, and exact description and specification of the same.

The object of the invention is to present a large surface to the air to be heated, and in such a position that the air passes readily upward between the heated surfaces, while at the same time the interior steam-passage of the radiator is well adapted to maintain the circulation of a current of steam and the removal of air by reason of such current.

The improvement has reference more particularly to indirect radiators for heating a current of air which, subsequently to being heated, is conveyed to rooms by pipes; but the improvements are applicable to radiators for all purposes.

The invention consists of a peculiar pin-surfaced loop-radiator, and of a combination of two or more rows of the same with a peculiar stepped base by which the steam is distributed to the several rows, all as recited in the claims at the close of this specification.

In order that the invention may be fully understood, we have represented in the accompanying drawings, and will proceed to describe, the best form in which we have thus far embodied our invention for practical use, it being understood that the same may be varied as circumstances or the views of different constructors or users may render expedient.

Figure 1 of said drawings represents a side view of our pin-loop radiator. Fig. 2 represents a face view of the stepped base with which we prefer to combine the said radiator for practical use. Fig. 3 represents a section of one of said pin-loop radiators combined with the said stepped base. Fig. 4 represents a top view of a part of the pattern by means of which the said pin-loop radiator is molded. Fig. 5 represents a transverse section of the

said pattern. Fig. 6 represents a transverse section of the green-sand mold for said pin-loop radiator, with the cores in place ready for pouring with melted iron.

The leading feature of the said radiator is 55 the pin-surfaced loop or pin-loop radiator A. This article is a pipe having two internal longitudinal passages, b b, which are connected at the closed end so as to constitute a loop by a cross-passage, c, and which communicate at 60 the opposite end of the loop with the base D, with which a series of such loops are combined for practical use. The exterior and interior of this loop are studded with pins e e e, by which the extent of radiating-surface is 65 greatly increased, while at the same time the free passage of air to be heated through the passage or opening f and at the peripheral edge of the loop is retarded by the pin-surface, so that the air has time to receive heat 70 from the radiator. The arrangement of the pins in the opening f and at the peripheral edge of the loop is important, because the pins so arranged protrude into the spaces through which the air moves and heat it more effectually. One or more rows of these pin-loop radiators are combined with a base, preferably 75 by constructing the open end m of the loop of circular cross-section and screwing it into an opening in the base. 80

For indirect heating the base is constructed with one or both of its sides in a series of steps, n n n, which are perforated with rows of holes, into which the pin-surfaced loops are fitted, and the steps have their faces constructed 85 at an angle with the plane of the base, so that the loops are inclined, as represented in the drawings, Fig. 3, whereby the delivery of condensed water is facilitated, and the horizontal area required for a radiator is reduced. The 90 base is made with suitable nozzles, r s, for the introduction of steam and the escape of condensed water, and these nozzles are by preference screwed internally, so that the supply and drip pipes can be readily connected with 95 them. We prefer to arrange the loops of each row opposite the intervals between the loops of the adjacent row, so as to cause the air to pass zigzag through the compound radiator.

The stepped construction of the base is im- 10.

portant, because it enables the centers of the seats or places of attachment of the loop-pipes to be set substantially in the same upright plane, notwithstanding the inclination of the 5 loops, so that the compound radiator occupies less space horizontally as compared with that which would be occupied if the inclined loops projected from an inclined continuous plane surface, in which case the outer ends of 10 each lower row of loops would project beyond those of the rows of loops above them.

We are aware that radiators have been made with pin-surfaces long previous to our invention; but in such cases they had but one internal passage for steam, and as this passage was heated practically uniformly throughout, the circulation was defective. The previous radiators, also being flat and broad, were necessarily too weak to withstand internal pressure, unless made of much greater thickness than is necessary with loop-pipes such as are represented in the drawings. The defects of the previous pin-surfaced radiators and their cost are so great that frequent efforts have 25 been made to overcome such defects, and we sought to do so by the production of loop-pipes with pin-surfaces. The first efforts were practically unsuccessful, because of the impossibility of molding such pipes by the ordinary methods, as the internal pins of the pattern cannot be drawn out of the mold when the patterns are made in the usual manner for smooth-surface loop-pipes. We have, however, discovered that pin-surfaced loop-pipes 30 35 may be readily molded by forming the part of the mold which makes the surfaces of the sides of the passage through the loop by means of dry-sand cores having their faces formed with cavities corresponding in form and size with the pins to be produced in casting the loop, while the parts of the mold at the outer surfaces of the loops may be made of green sand, provided the patterns are made in sections, parts of which may be moved crosswise of the direction in which the pattern is drawn from the sand.

We prefer to make the pattern for molding the pin-loop radiators as represented in Figs. 4 and 5, the pattern being divided at the line

u u into halves connected by pins, and each half being formed of three members, H I I. The side members, I I, are connected with the central member, H, by means of dovetail tongues t t, fitting into corresponding grooves and tapered from the outer faces of the pattern 55 to the dividing-line u u thereof. The side members have pin projections e' e', corresponding with the pins to be produced by casting. The pattern is molded in a two-part flask of ordinary construction, and the central member, H, 60 of each half is drawn first from the sand, after which the side members, I I, may be drawn from the sand by moving them crosswise until their pin projections are free of the sand. The dry-sand cores for the central passage of the 65 loop are made and dried in the usual manner, their section being shown at J J in Fig. 6. They and the pipe-cores K K are inserted in the mold before the flask is closed, so that when the mold is ready for being poured with 70 the molten metal its cross-section is as shown in Fig. 6.

Having thus described our invention, we declare that we do not claim radiators having their broad flat surfaces studded with pins. 75 We are aware, also, that radiating pipes and tubes have been projected laterally and upwardly from bases, and therefore do not claim, broadly, that combination; nor do we claim the combination of rows of pipe-radiators with 80 a base having an inclined continuous plane surface from which the radiator-pipes project.

We claim as our invention—

1. The pin-loop radiator, substantially as before set forth, consisting of a loop-pipe having the edges of the loop studded with pins in one piece with the pipe.

2. The combination, substantially as before set forth, of rows of pin-loop radiators with a hollow stepped base-plate.

In witness whereof we have hereto set our hands this 15th day of June, A. D. 1883.

THOS. H. WILLIAMS.
S. D. TOMPKINS.
JOHN N. MATLOCK.
